(No Model.)

J. F. MUIR.

MAIL, PARCEL, OR CASH CARRIER.

No. 373,997.

Patented Nov. 29, 1887.

UNITED STATES PATENT OFFICE.

JOHN F. MUIR, OF TOPEKA, KANSAS.

MAIL, PARCEL, OR CASH CARRIER.

SPECIFICATION forming part of Letters Patent No. 373,997, dated November 29, 1887.

Application filed March 29, 1887. Serial No. 232,895. (No model.)

To all whom it may concern:

Be it known that I, JOHN F. MUIR, a citizen of the United States, residing at Topeka, in the county of Shawnee and State of Kansas, 5 have invented certain new and useful Improvements in Mail, Parcel, or Cash Carriers; and I do hereby declare the following to be a full, clear, and exact description of the invention, such as will enable others skilled in the art to 10 to which it appertains to make and use the same.

My invention relates to devices for carrying mail to or from the street or sidewalk to a house or parcels, packages, or cash in business-houses. It is especially designed to meet a 15 want in rural districts, villages, and small towns where dwelling-houses are set back a considerable distance from the street or sidewalk, and in consequence thereof much time is lost on the part of the mail-carrier and the news-boy in being required to walk from the street to the house, and in rural districts it will enable a mounted postman to deliver mail without dismounting or some person going from the house to receive mail, as is now the practice. 20

The invention is not, however, limited in its use to mail-service, but may be applied to stores and other business-houses as a parcel, package, or cash carrier.

30 I shall hereinafter describe my invention, and particularly point it out in the claims.

In the accompanying drawings, which form a part of this specification, Figure 1 represents a side view, partly in section, and Fig. 35 2 a vertical transverse section.

Reference being had to the drawings and the letters marked thereon, A B represent posts, between which are stretched wires a b, which support a carrier, C, which may be of 40 any suitable form or construction. In the present instance I have shown eyebolts c c in the sides of the carrier, through which the wires a b pass and upon which the carrier slides from one post to the other. The receiver 45 may, however, be supported upon suitable grooved wheels mounted upon axles secured to the carrier.

D represents a rod projecting inwardly from each post, and near the outer end thereof is a 50 hook or projection, d, with which a rod or chain, e, engages. To the ends of the rod e are secured one end of the springs f f, the op-

posite ends of which engage with eyes g g in the sides of the carrier C.

Instead of the two springs f f, one larger 55 spring may be applied to the end of the carrier and the posts A and B. On the upper side of the carrier are angular projections g' g', with which the notch h on the under side of the latch or trigger i engages to draw the carrier toward the posts A B, as will hereinafter more fully appear. On the upper side of the latch is formed a notch, k, which enables the latch to rise and disengage from the angular projection g', and also limits the rearward 60 motion of the latch.

E E' represent cords, one end of each of which is secured to one of each of the latches i, as shown at l. The cord passes over a sheave, m, upon which the lower side of the 70 latch rests, and forms a fulcrum to trip the latch when it is drawn back from the opposite end of the structure.

The cords E E' extend from one latch, i, to the opposite end of the structure, and constitute suitable means for drawing the carrier back toward the posts. Upon the posts A B are secured signal-bells F G, which are struck by a hammer, n, secured to a rod, o, which passes through an eye, o', on the latch i, and 80 gives an alarm whenever the carrier C is released at either end.

The several parts being constructed substantially as described, the operation is as follows: The carrier C being at either end of the line and 85 the latch i in engagement with one of the projections g', mail, parcels, packages, or cash is or are placed in the carrier, when the cord E or E' projecting through the post at the opposite end is pulled, which draws the carrier C toward 90 the post A or B, and puts the springs f f under tension, as shown in dotted lines at post A in Fig. 1. When the latch i reaches the position shown in dotted lines, the sheave m acts as a fulcrum to the latch and tilts its front end 95 up, which disengages it from the projection g', when the resiliency of the springs f f thrust or force the carrier across the wires a b to the opposite end of the line or structure. As the latch i returns to its normal position, it carries the rod o forward, and the hammer n strikes the signal-bell F or G, according to the 100 end from which the carrier is sent.

In the application of my invention to carry-

ing mail one end of the wires may be secured to a post of a portico, or to a post near the house for the purpose, and the other end to a gate-post, when the wires may be conducted 5 along the path or walk leading from the house to the street or sidewalk. The carrier will be kept normally at the house end of the line. When a mail-carrier or newsboy wishes to deliver mail or papers, he pulls upon the cord 10 E at the street end of the line, which will release the carrier, force it across the wires *a b*, and strike an alarm, thus calling the attention of the inmates of the house to the fact that some 15 person wishes to use the carrier. Mail, news-papers, or other matter having been placed in the carrier, the cord E' at the house end is pulled, when the carrier will be forced toward the house.

Having thus fully described my invention, 20 what I claim is—

1. A track supported at both ends by suitable posts, a carrier provided with springs, and a rod connecting said springs, in combination with a bar below the track secured to 25 one of said posts and provided with a projec-

tion, a latch above the track supported by the post, a projection on the carrier, and a cord extending from the latch to the opposite end of the structure, substantially as described.

2. In combination with a track, a carrier 30 provided with a suitable projection, a latch having shoulders on its upper and lower sides which engage with the projection on the carrier and with the post, respectively, a cord attached to the latch, a sheave in the rear of the 35 latch, arranged in its path and adapted to trip the latch, and a spring or springs, substantially as described.

3. In combination with a track, a carrier supported by the track, a latch engaging with 40 the carrier, a signal-bell, a hammer connected to the latch, a cord, a sheave, and a spring or springs for propelling the carrier and striking the bell, substantially as described.

In testimony whereof I affix my signature in 45 presence of two witnesses.

JOHN F. MUIR.
